CHARLES BOURGEOIS, OF BUFFALO, NEW YORK.

Letters Patent No. 90,988, dated June 8, 1869.

IMPROVEMENT IN COMBINED STEAM AND VACUUM-GAUGE.

The Schedule referred to in these Letters Patent and making part of the same.

To all whom it may concern:

Be it known that I, CHARLES BOURGEOIS, of the city of Buffalo, county of Erie, and State of New York, have invented certain Improvements in Steam and Vacuum-Gauges; and I do hereby declare that the following is a full, clear, and exact description thereof, reference being had to the accompanying drawings, making a part of this specification.

The nature of my invention consists in combining within the same enclosing-case the mechanism of a steam-gauge and the mechanism of a vacuum-gauge, when so arranged that the index-hand of the steam-gauge is concentric with, yet independent of that of the vacuum-gauge.

In the accompanying drawings—

Figure I is a front elevation of my improved gauge, with a portion of the case and index-plate broken away, so as to show the internal mechanism.

Figure II is a cross-sectional elevation of the same.

Like letters designate like parts in each of the figures.

A represents the enclosing-case, the front of which is made open, but covered by a glass plate, A¹, held by the screw-rim A² in a common manner.

B represents the capsule of the steam-gauge. It is composed of two elastic metal plates or disks riveted to an interposed ring, so as to form a steam-tight chamber between them.

To the lower plate is secured a hollow shank, B¹, which passes through the side of the case A, and has a shoulder, b², and jam-nut, b³, by which it is firmly secured to the case.

To the outer end of the shank is attached the pipe conducting the steam from the boiler into the capsule. The pressure of the steam within the capsule will cause the elastic plates thereof to swell outward in proportion to the pressure, and it is this movement of the capsule which is made to operate an index-hand, and indicate, upon a properly-graduated scale, the amount of said steam-pressure.

C represents the pinion-spindle of the steam-gauge located centrally within the case, and having bearings in a frame, D, D¹, and D², secured to the back side of the case by screws, as shown at d³.

E E¹ represent the combined lever and gear-segment by which the expansion of the capsule is made to actuate the pinion-spindle c. The axis or shaft of this segment has bearings in the frame D D¹, as shown at e², contiguous to the upper plate of the capsule, so that the lever E¹ projects parallel, or nearly so, to the face of the capsule, while the gear-segment meshes with the pinion c.

An adjustable bearing-piece, F, is attached to the end of lever E¹, which rests in contact with the capsule, at or near the centre of the same, so that the movement of the capsule, which takes place under an in-

crease or diminution in the steam-pressure, will correspondingly move the lever and gear-segment, and therefore the pinion-spindle c.

An index-hand, G, mounted on the end of pinion-spindle c, will indicate the amount of movement in the capsule upon a properly-graduated index-plate, H, as in common gauges.

A volute-spring, I, applied to the pinion-spindle in a common manner, returns the parts under a contracting movement of the capsule, and a stop-screw, I¹, prevents the segment from returning too far.

It is found that equal additions to the steam-pressure do not produce a corresponding increase in the expansion of the capsule, and that, therefore, with an invariable length of lever E¹, the angular movements of the index-hand would not be equal for such equal additions, but would grow gradually less as the pressure increased, which would require the divisions of the index-plate to be graduated to correspond.

It is desirable that the divisions of the index-plate should be uniform. To permit this, I make the bearing-piece F with considerable length in the direction of the lever, so that as the pressure increases, and the capsule expands, the working length of lever E¹ will decrease, which will have the effect to increase the movement of the segment for a given expansion of the capsule, and thereby accomplish the desired result.

The capsule J, hollow shank K, lever and gear-segment L L¹, adjustable bearing-piece M, stop-screw N, and frame D D¹ D² are parts of the vacuum-gauge, which parts are constructed and arranged with each other in a similar manner to that of the corresponding parts of the steam-gauge.

P is the index-hand of the vacuum-gauge, attached to a sleeve-spindle, Q, surrounding the spindle c, and having for its bearing the stationary sleeve r, secured to the frame D¹.

S is a pinion mounted on the spindle Q, and operated by the segment L¹, with which it meshes.

A volute-spring, I¹, is applied to the sleeve-spindle, in such a manner as to cause the pinion S to actuate the segment as the capsule collapses, and thereby keep the bearing-piece in contact therewith; the operation of this spring being similar to that of the spring I, before described.

The dial-plate is provided with two concentric index-scales t t¹, properly graduated and numbered, to correspond with the respective hands G P, the one to which the inner scale is adapted being preferably made a little shorter than the other, for ease of distinction. The hands may also be made of different color, for the same purpose.

It is evident that action of the capsule of the vacuum-gauge will be the opposite of that of the steam-gauge, the vacuum contracting the sides of the capsule of the one, while the steam expands the sides of the other in

the well-known manner of such gauges when made separate.

What has been previously stated respecting the unequal expansion of the capsule of the steam-gauge, and of the means employed (the convex surface of the bearing-piece) to compensate therefor, will be equally true with respect to the unequal contraction of the sides of the vacuum-capsule, the compensation being effected in a similar manner.

It will also be perceived that while the two gauges are combined in one case, so as to form in some respects a single instrument, yet the operation of each is as perfect, and as entirely independent of the other as though they were separate and distinct instruments.

By the use of my improvements a great saving is

obviously effected in the cost of manufacturing such gauges.

My combined instrument is also more convenient, as a single view of the dial will furnish the required information as to the state of both gauges.

What I claim, and desire to secure by Letters Patent, is—

The combination of the mechanism of a steam-gauge and the mechanism of a vacuum-gauge within a cylindrical enclosing-case, so arranged as to actuate concentric index-hands over the same dial-plate, substantially as herein described.

Witnesses: CHARLES BOURGEOIS.
